UNITED STATES PATENT OFFICE.

ALPHONSO H. COBB, OF ROCKLAND, MAINE.

FOUNTAIN-PEN.

SPECIFICATION forming part of Letters Patent No. 357,176, dated February 8, 1887.

Application filed September 18, 1886. Serial No. 213,872. (No model.)

To all whom it may concern:

Be it known that I, ALPHONSO H. COBB, a citizen of the United States, residing at Rockland, in the county of Knox and State of Maine, 5 have invented a new and useful Improvement in Fountain-Pens, of which the following is a specification.

My invention has relation to that class of fountain-pens wherein the holder, constituting 10 a cistern for the ink-supply, is arranged to receive an ordinary split-nib pen, and is provided with devices for conveying the ink from the cistern to the pen.

The objects of my invention are to simplify 15 the construction, to reduce the number of parts, to render the feeding device instantaneously adjustable to any style or size of pen, and readily removable for cleansing if the ink becomes thick or clogged.

20 It consists in the devices illustrated in the accompanying drawings, as hereinafter described and claimed.

In the accompanying drawings, which are enlarged one diameter in excess of the actual 25 size, Figure 1 is an elevation, and Fig. 2 a longitudinal central section, of a pen and holder embodying my invention.

The holder A consists of a hollow case, preferably of hard rubber, closed at the upper end 30 and having in the lower end a stopper, B, of the same material. The lower end of the stopper B is a hollow cylinder, in which is inserted a split conical screw-plug, C, retained by being screwed into a recess in the stopper B; and 35 which, with the inner face of said cylinder, forms a recess for the reception of the pen D.

Through the screw-plug C and stopper B is an orifice running diagonally from near the center of the pen to the opposite end of the 40 stopper B, close to its outer face. In this orifice is inserted a slender strip, E, of elastic material—such as rubber, whalebone, or the like—which fits loosely therein, and the ends of

which project therefrom in each direction and press, respectively, on the inner faces of the pen 45 D and holder A. The pressure of the lower end against the pen is slight, and only sufficient to insure contact therewith at all times, and it can be instantly moved in either direction to rest near or remote from the pen-point. 50 The upper end projects so far beyond the stopper B that the part which rests against the inner face of the holder A is, by friction therewith caused by its own tension, retained in place. 55

In operation, the holder being filled with ink and a pen properly placed therein, the strip E is drawn outward to a position near the point of the pen, preferably about one-eighth of an inch therefrom. The ink, by capillary attraction, flows through the orifice around the strip E, and, following it, is conveyed to the pen-point. 60

It is obvious that the upper end of the holder A may be closed by a removable cap, and that 65 a solid partition integral with the holder may be substituted for the stopper B without departing from my invention, the essential features of which are, and which I claim—

In a fountain-pen of the species described, 70 the hollow holder A, forming an ink-cistern, and having at its lower end a recess for the pen, and between said recess and cistern a partition through which is a diagonal orifice in which rests a strip of elastic material, the ends 75 of which press, respectively, the inner faces of the pen and cistern, substantially as shown, and for the purpose specified.

In testimony that I claim the foregoing I have hereunto set my hand this 28th day of 80 August, A. D. 1886.

ALPHONSO H. COBB.
